CLAIM

The ornamental design for a flash drive clip, as shown and described.

DESCRIPTION

FIG. 1 is a perspective view of a flash drive clip showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

FIG. 8 is a perspective view thereof, wherein the flash drive clip is shown in a second configuration exposing the electrical connectors of the flash drive.

The broken line showing of the electrical connectors in FIG. 8 are for the purpose of illustrating unclaimed portions of the flash drive clip and form no part of the claimed design.
